UNITED STATES PATENT OFFICE.

SAMUEL E. CALVIN, OF TERMINAL ISLAND, CALIFORNIA.

DEHYDRATING ATTACHMENT FOR FLASH TESTERS.

Application filed October 31, 1927. Serial No. 230,197.

In testing oils which contain water for flash point in the well known "closed cup" instruments, difficulty is often experienced due to the presence in the oil vapor of variable 5 quantities of water vapor, by which an accurate flash test reading is made difficult or impossible.

This difficulty has its basis in the fact that, in closed cup instruments, there is no means 10 for complete escape of the water vapor, and as a mixture of water vapor and oil vapor is less readily ignited than a pure oil vapor, an oil containing water must be heated to a higher 15 temperature to produce the flash than the same oil free from water. The test or flash- ing temperature is thus raised, by the presence of water, to a material and indeterminate degree above the true test.

I have discovered that by placing in the 20 vapor space within the flash cup an absorbent for water vapor, such vapor may be removed as fast as formed, and the true flash test ob- tained with facility in oils containing any 25 commonly occurring proportion of water.

A preferred means for applying my inven- 30 tion is illustrated in the attached drawings, in which

Figure 1 is a vertical section of a flash 35 tester cup containing my improved vapor dehydrator.

Figure 2 is a plan view of Figure 1, and

Figure 3 is a plan view of the dehydrator basket indicated at 3 in Figure 1.

Referring to the figures, 1 is the oil cup of any closed flash tester, which is filled with oil 35 to a fixed height as indicated at 2. 3 is a ring shaped shallow basket formed of fine brass wire mesh, supported on the upper edge of the oil cup (below the cover not shown) by the hooks 6—6—6. In the plan view, Fig. 40 40 figure 3, the openings 4 and 5 through the basket are to admit the test flame and the thermometer respectively. The cup is supported in the heating bath by the usual flange 7. The basket is to be filled for use with coarse granu- 45 lated calcium clorid or other solid dehydrat- ing agent, which must be discarded and re- placed when it loses its capacity for absorb- ing water.

It will be understood that the flash cup 50 described is no part of my invention, which resides solely in the dehydration of oil vapors within any such cup and in the means for such dehydration.

I claim as my invention:

In combination: a closed cup flash tester and a receptacle within the cup of said tester for retaining a dehydrating agent, said receptacle communicating with the interior of said cup for permitting contact of said dehydrat- 55 60 ing agent with vapors of the oil being tested.

In witness that I claim the foregoing I have hereunto subscribed my name this 20th day of September, 1927.

SAMUEL E. CALVIN.
